UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,398,589.

Specification of Letters Patent. Patented Nov. 29, 1921.

Application filed November 19, 1920. Serial No. 425,082.

To all whom it may concern:

Be it known that I, CLARENCE B. FOWLER, a citizen of the United States, residing at New York, in the county of New York and 5 State of New York, have invented certain new and useful Improvements in Telephone-Exchange Systems, of which the following is a full, clear, concise, and exact description.

10 This invention relates to telephone exchange systems and particularly to a new and improved toll switching trunk circuit for connecting a common battery toll switchboard with a magneto switchboard.

15 Previous to this invention, it was the practice in establishing a trunk connection between a common battery toll switchboard and a magneto switchboard, to use a toll switching trunk, of the type regularly used 20 in making connection with a common battery office. Used in this way, the trunk supervisory signal did not function as when used for a common battery connection, necessitating, therefore, monitoring by the operator in order to assure proper supervision.

30 It is an object of this invention to provide a trunk circuit which may be used for extending a connection from a common battery toll switchboard to a magneto switchboard, and which will have all the 35 advantageous features of common battery supervision.

To attain this object, in accordance with 40 one feature of the invention, means is provided so that the actuation of the magneto generator at the substation causes the display of the trunk supervisory signal in the connecting cord circuit at the toll switchboard.

45 To further attain this object in accordance with another feature of this invention, means is provided so that a subscriber's station on a magneto line may be selected and signaled from the toll switchboard.

50 In accordance with a third feature of the invention, there is a provision of means whereby in the event of the called line being found "busy," the trunk supervisory signal of the connecting toll cord circuit may be caused to flash intermittently.

55 These and other features of the invention not specifically mentioned above will more fully appear from the following specification and accompanying drawing in which

the figure shows one embodiment of the invention.

In the drawing there is shown, a toll cord circuit A which may be one of a plurality of similar cord circuits appearing at 60 an operator's position at a toll switchboard. Since this cord circuit is not a part of the invention, only a part sufficient to explain the working of the invention is shown. B is a toll switching trunk circuit consisting 65 of two sections, with inductive magnetic coupling consisting of a repeating coil 19. The inductive coupling might, however, be of the electrostatic type, consisting of a condenser. It terminates in a plug 11 at 70 an operator's position of a magneto switchboard, and may be one of a plurality of similar circuits. It is adapted to extend connections from a cord circuit A at the toll switchboard to any one of a plurality 75 of magneto subscribers' lines terminating at the "B" or switching position of a magneto switchboard, one of which, C, is shown connected to a jack 12 at the contacts of which is shown connected a line signal 15, 80 which may be actuated by the operation of a magneto generator at a subscriber's station, 30. A busy back circuit D terminating in a jack 34 within reach of the magneto switchboard operator is also shown. 85 When the called subscriber's line is found engaged, the plug 11 is inserted into the jack 34 whereby an interrupter 25 causes interrupted current to be transmitted over trunk B causing thereby an intermittent 90 actuation of a trunk supervisory signal 32 in the toll cord circuit A.

It is thought that this invention may be more fully understood from the following description of the operation of the system 95 as shown on the drawing.

When the toll operator in control of the cord circuit A desires to extend a connection to the subscriber's station 30 shown connected to line C, a trunk assignment will be 100 obtained from the operator at the magneto switchboard in control of the incoming end of the trunk circuit B over a call wire circuit (not shown). Assuming that the trunk circuit B is assigned, the toll operator inserts 105 plug 1 into jack 2, which causes the operation of relay 3 over the following circuit: from grounded battery through resistance 5, sleeve contacts of plug 1 and jack 2, and winding of relay 3 to ground. Relay 3, in operat- 110

ing, causes the illumination of lamp 7 over the following circuit: from grounded battery through lamp 7, normal contact of relay 9 and right-hand alternate contact of relay 3 to ground. The illumination of lamp 7 serves as a guard signal to the magneto operator indicating that the toll operator has plugged into the assigned trunk. The magneto switchboard operator then inserts plug 11 into jack 12 causing the operation of relay 9 over the following circuit: from grounded battery through the windings of relays 14 and 9, sleeve contacts of plug 11 and jack 12, and resistance 28 to ground. Relay 14 being marginal does not obtain sufficient current in this circuit to operate, but relay 9 operates and by opening its normal contact extinguishes lamp 7. The left-hand alternate contact of relay 9 is closed and causes the slow operating relay 16 to operate over an obvious circuit. Relay 9 is of the slow operating type so that the tip and ring conductors will not be connected through until the plug 11 is completely inserted in jack 12. Otherwise relay 21 might operate from battery in the sleeve circuit, due to a momentary crossing of the plug and jack conductors, when the plug is being inserted. The operation of relay 16 closes a through circuit for the tip and ring conductors and establishes a conversational path from cord circuit A to the subscriber's station 30. The insertion of plug 11 into jack 12 also causes the disconnection of line signal 15 at the normal contacts of jack 12.

The toll operator after inserting plug 1 into jack 2 actuates the ringing key 37, ringing according to the necessary code to select the called subscriber's station 30, which is connected to the party line C. The path of the ringing current may be traced as follows: from source of ringing current 18, lower alternate contact of key 37, ring contacts of plug 1 and jack 2, lower normal contact of relay 22, winding of repeating coil 19, upper normal contact of relay 22, tip contacts of jack 2 and plug 1, and upper alternate contact of key 37 to ground. Ringing current will be induced in the secondary windings of repeating coil 19 and will be transmitted over the tip and ring conductors including the contacts of relay 16, tip and ring contacts of plug 11 and jack 12, and the tip and ring conductors of line circuit C to bell 6 at substation 30. Station 30, upon the removal of the receiver from the hook is now in conversational connection through the repeating coil 19 with cord circuit A and the toll line (not shown) with which the answering end of cord circuit A (not shown) is connected. On completion of the conversation, key 31 at station 30 is actuated and then the magneto generator 26 is operated. Current is then transmitted over both the tip and ring conductors of line circuit C as follows: from

ground through the upper alternate contact of key 31, armature and contact of generator 26 to the ring conductor, also through the lower alternate contact of key 31, to the tip conductor. This current passes in parallel over both tip and ring conductors, tip and ring contacts of jack 12, plug 11, contacts of relay 16, upper and lower right-hand windings of repeating coil 19 to the center point between these windings and thence through the winding of relay 21 to ground. Relay 21 operates to cause the operation of relay 22 over an obvious circuit connecting thereby battery and ground to the ring and tip conductors of trunk circuit B as follows: from grounded battery through the lower winding of retardation coil 29, lower alternate contact of relay 22, ring contacts of jack 2 and plug 1, winding of relay 27, tip contacts of plug 1 and jack 2, upper alternate contact of relay 22, and upper winding of retardation coil 29 to ground. Relay 22, upon operating locks up through the following path: from grounded battery through the winding and middle alternate contact of relay 22, contact of relay 14, and left-hand alternate contact of relay 3 to ground. Relay 27 operates and causes the illumination of lamp 32 over an obvious circuit. The toll operator upon noting the glowing of lamp 32, connects an operator's telephone set (not shown) to the cord circuit A by actuation of listening key 23. Although relay 22 is operated, opening the tip and ring conductors, at its upper and lower normal contacts, a talking path is still provided through condensers 4 and 10. Upon ascertaining that the glowing of the lamp 32 is a disconnect signal, the toll operator withdraws plug 1 from jack 2 and releases relay 3. This again causes the illumination of lamp 7 which is now a disconnect signal to the magneto switchboard operator who withdraws plug 11 from jack 12, thereby returning all apparatus to normal. If however, a disconnection is not desired the operator withdraws plug 1 only for an instant, so as to release relay 3 momentarily, and thereby open the locking circuit of relay 22, so that this relay will release and cause the extinguishing of the supervisory lamp 32.

If, when the toll operator in control of cord circuit A, requests over the call wire circuit (not shown) a connection to station 30, it is found that the line circuit C is engaged, the magneto switchboard operator, instead of inserting plug 11 into jack 12, inserts it into jack 34, causing thereby the operation of relays 36, 9 and 14 over the following circuit: from grounded battery through the winding of relays 14 and 9, sleeve contacts of plug 11 and jack 34, resistance 35 and winding of relay 36 to ground. Under this condition, relay 14 now operates due to the low resistance of resistance 35 and relay 36.

When relay 36 operates, it closes an obvious circuit from interrupter 25 through the winding of relay 24 causing the latter relay to operate intermittently. Relay 9 upon operating again causes the operation of slow operating relay 16 which connects through, at its alternate contacts, the tip and ring conductor of the trunk circuit B. The intermittent operation of relay 24 causes the intermittent 10 operation of relay 21 over the following circuit: from grounded battery, through the contact of relay 24, resistance 33, ring contacts of jack 34 and plug 11, lower contact of relay 16, winding of repeating coil 19 and winding of relay 21 to ground. The intermittent operation of relay 21 will likewise cause through an obvious circuit the intermittent operation of relay 22, which no longer locks through its middle alternate 15 contact, because the locking circuit is broken at the contact of relay 14. The intermittent operation of relay 22 causes the intermittent operation of relay 27, over the circuit previously traced, and the flashing of trunk supervisory lamp 32. The toll operator observing the flashing is advised thereby of the busy condition of the line circuit C and upon withdrawing the plug 1 from jack 2 causes the release of relay 3, and the lighting of 20 lamp 7 as a disconnect signal. Plug 11 is then withdrawn from jack 34, and all apparatus is restored to normal.

Cord circuit A is also provided with a relay 18, which in series with the condenser 17 is connected across the line. This relay when energized by ringing current incoming from the connected toll line (not shown), causes the operation of relay 8, and the lighting of lamp 32 over obvious 25 circuits. Relay 8 locks up through a circuit including its own contact and the normal contact of key 23. The operator upon noting the glowing of lamp 32, operates listening key 23 to supervise the connection 30 and by so doing, opens the locking circuit of relay 8 and extinguishes lamp 32.

What is claimed is:

1. In a telephone exchange system, a subscriber's line circuit, a subscriber's station on said line, a source of current at said station, an operator's position, a cord circuit associated with said operator's position, a supervisory signaling device associated with said cord circuit, a link circuit 50 for extending a connection from said cord circuit to said line circuit, means for opera-

ting said supervisory signaling device from said station in response to the source of current thereat so as to be steadily operated, an interrupter circuit for connection to the link circuit, and means for intermittently operating said supervisory signaling device when said link circuit is connected to said interrupter circuit. 60

2. In a telephone exchange system, a subscriber's line circuit, a subscriber's station on said line, a source of current at said station, an operator's position, a cord circuit associated with said operator's position, a supervisory signaling device associated 70 with said cord circuit, a link circuit for extending a connection from said cord circuit to said line circuit, a relay responsive to the source of current at the subscriber's station, a locking circuit for said relay, means for causing the relay to lock through said circuit, means for causing the said supervisory signaling device to be steadily operated in response to the actuation of said relay, an interrupter circuit for connection 75 to the link circuit and means for opening the locking circuit when the trunk circuit is connected to the interrupter circuit thereby operating said relay intermittently to cause an intermittent operation of said supervisory signaling device. 80

3. In a telephone exchange system, a subscriber's line circuit, a cord circuit, a supervisory signaling device associated with said cord circuit, a link circuit for extending a 90 connection to said line circuit, an interrupter circuit for connection to the link circuit, a relay responsive to current in the trunk conductors, said relay controlling said supervisory signaling device, a locking circuit for said relay, a second relay controlling said locking circuit, means associated with said line circuit for preventing the operation of the said second relay when the link circuit is connected with the line circuit, 95 and means associated with said interrupter circuit for operating said second relay when the link circuit is connected to the interrupter circuit, to open the locking circuit of the first mentioned relay for placing said first mentioned relay under control of said interrupter circuit to intermittently operate said supervisory signal. 100

In witness whereof, I hereunto subscribe my name this 9th day of November, A. D., 110 1920.

CLARENCE B. FOWLER.
